FIG. 1 is a perspective view of a promotional intravenous fluid bag replica clock showing my new design;

FIG. 2 is a front elevational view of the embodiment of FIG. 1;

FIG. 3 is a top plan view of the embodiment of FIG. 1;
FIG. 4 is a side elevational view of the embodiment of FIG. 1;

FIG. 5 is a side elevational view thereof, opposite that shown in FIG. 4, of the embodiment of FIG. 1;

FIG. 6 is a bottom plan view of the embodiment of FIG. 1; and,

FIG. 7 is a rear elevational view, of the embodiment of FIG. 1.

The broken lines shown herein are for illustrative purposes only and form no part of the claimed design.
